(57) **CLAIM**

The ornamental design for an epilator, as shown and described.

DESCRIPTION

The patent or application file contains drawings executed in color. Copies of this patent or patent application publication with color drawings will be provided by the Office upon request and payment of the necessary fee.

FIG. 1 is a perspective view of an epilator;

FIG. 2 is a front view thereof;

FIG. 3 is a right side view thereof;

FIG. 4 is a rear view thereof;

FIG. 5 is a left side view thereof;

FIG. 6 is a top plan view thereof;

FIG. 7 is a bottom view thereof.

FIG. 8 is a perspective view of an epilator;

FIG. 9 is a front view thereof;

FIG. 10 is a right side view thereof;

FIG. 11 is a rear view thereof;

FIG. 12 is a left side view thereof;

FIG. 13 is a top plan view thereof; and,

FIG. 14 is a bottom view thereof.

Color drawings are being submitted because color is an integral part of some embodiments of the claim design.

**1 Claim, 6 Drawing Sheets
(4 of 6 Drawing Sheet(s) Filed in Color)**
